TELEPHONE SYSTEM

Filed Dec. 29, 1931

UNITED STATES PATENT OFFICE

JOHN A. BURGENER, OF HINSDALE, ILLINOIS, ASSIGNOR, BY MESNE ASSIGNMENTS, TO ASSOCIATED ELECTRIC LABORATORIES, INC., OF CHICAGO, ILLINOIS, A CORPORATION OF DELAWARE

TELEPHONE SYSTEM

Application filed December 29, 1931. Serial No. 583,667.

The present invention relates to telephone systems in general, but is more particularly concerned with telephone systems wherein the subscribers' lines are classified and where-
 5 in provisions are made for informing the telephone operator answering a call of the class to which the calling line belongs; and the main object, broadly stated, is to provide a more refined and satisfactory arrangement
 10 for notifying the operator of the class in which the calling line belongs.

General description

The present invention is an improvement
 15 on the arrangement disclosed in the application of Victor S. Tharp, filed January 29, 1931, serial No. 512,047 now Patent No. 1,868,956, July 26, 1932. In the Tharp disclosure, when an automatic subscriber dials
 20 a special number and causes the automatic switching apparatus to operate to extend his connection to a manual switchboard by way of a trunk line leading from the automatic switchboard to the manual switchboard, the
 25 manual operator is signalled; while, at the same time, the release trunk conductor of the connection established from the calling line to the automatic-to-manual trunk line is inductively coupled with the talking circuit, so
 30 that, when the operator answers, any tone current placed on the release-trunk conductor of the established connection by way of the subscriber's individual line equipment is heard by the operator for a predetermined in-
 35 terval of time after the operator responds. Now, it often happens during certain so-called busy periods that the manual operator is unable to respond promptly, with the result that several unanswered connections
 40 may extend to her switchboard at the same time. With the tone current being simultaneously applied to several of the inter-
 45 switchboard trunk lines, which are often ex-
 50 fore of considerable length, some difficulty is experienced in preventing the tone current from being induced in the parallel trunk lines over which conversation is taking place. The amount of unwanted tone current in-
 55duced in a parallel circuit as a result of the application of tone current to a single trunk line is ordinarily not objectionable, especially if the application of tone current is only momentary. It can be readily seen, how-
 ever, that the induced current in circuits over

which conversation is being carried out may become of annoying magnitude when tone current is being continuously applied to several trunk lines over which unanswered connections have been extended to the manual 60 switchboard. If the application of tone current to an inter-switchboard trunk line is made only after the operator responds and then only for a long enough time to enable the operator to distinguish the character of 65 the tone signal, the situation discussed above is at once remedied, as the operator answers the calls one at a time, and the currents induced in foreign circuits are only momentary and of a magnitude so small as to be practical- 70 ly unnoticeable.

The specific object of the invention may now be stated to be the provision of suitable circuit arrangements in a system such as outlined briefly above for bringing about an 75 application of the distinctive tone current to the inter-switchboard trunk line responsive to the call being answered by the operator and for automatically discontinuing the application of tone current at the end of a pre- 80 determined interval long enough to enable the operator to distinguish the character of the tone signal.

It is understood, of course, that systems have been developed heretofore wherein the 85 application of tone current to the inter- switchboard trunk line is made only after the operator responds and is terminated after the operator has heard and distin- guished the characteristic tone signal; but, as 90 far as applicant is aware, this is the first time that this operation has been performed entirely automatically responsive to the simple answering act of the operator performed in the usual manner and without necessitating a 95 special key manipulation or other similar special acts on the part of the operator to initiate or terminate the application of the tone current.

Description of drawing

100

Referring now to the accompanying single sheet of drawing, the showing therein is similar to the showing in the drawings in the Tharp application hereinbefore referred to; the main difference lies in the arrangement employed in the so-called repeater or trunk circuit TC connected on the automatic- switchboard end of the inter-switchboard trunk line comprising conductors 23 and 24. 110

The lineswitch LS is the usual rotary line-switch ordinarily provided individual to a subscriber's line, while the selector S is a schematically represented first selector of the 5 regular Strowger type. From one of the levels of this selector, a number of automatic-to-manual trunk lines may be reached, one of which is the trunk line comprising conductors 23 and 24 and having the trunk 10 circuit TC inserted therein for exercising the necessary control of the various functions pertaining to setting up, supervising, and releasing the connection. Each trunk line terminates at the manual switchboard in a jack, 15 such as the jack J, illustrated, and each trunk line has a line circuit associated therewith at the switchboard, such as the line circuit LC. A number of cord circuits, such as the cord circuit CC, are provided, which cord 20 circuits are preferably of the general type disclosed in Patent No. 1,802,449, granted April 28, 1931 to A. W. Steinke.

It will be noted that two tone sources are 25 shown associated with the lineswitch LS, the tone transformers 25 and 26. The operating current for the operating magnet 1 of the lineswitch LS may be obtained through the secondary winding of either tone transformer depending upon the class in which 30 the line of substation A belongs. As shown, the operating current for the lineswitch magnet is obtained through the secondary winding of the transformer 25, through 35 which the first of the two characteristic tones is supplied, denoting that the line of substation A belongs in the first class. It will be understood, of course, that the number of classes may be extended as desired by providing additional tone sources. 40

Detailed description

The invention having been described generally, a detailed description of the operation of the apparatus shown will now be 45 given. For this purpose it will be assumed that the subscriber at substation A removes his receiver and dials the digit assigned to the manual switchboard for the purpose of soliciting the aid of the manual operator in 50 establishing a connection which may not be established directly through the automatic switchboard.

Seizing the truck circuit TC

55 When the receiver is removed at substation A, the line relay 3 of the lineswitch LS operates in the usual manner and connects up the magnet 1 for operation, at the same time enabling switching relay 2 to operate (as soon 60 as an idle trunk is found) and extend a connection by way of wipers 4 to 6 to this trunk. Assuming that the trunk line extending to the selector S is the first one found to be idle, the selector S is seized and thereupon prepared for operation in the usual manner.

When the digit assigned to the switchboard of the manual operator is dialled, the selector S responds by raising its wipers opposite the desired level of bank contacts and then rotates them in the usual manner in 70 search of an idle trunk line. Assuming that the trunk line shown in the drawing is the first one found to be idle, this trunk line is seized by the selector S by way of conductors 7, 8, and 9; whereupon the line relay 10 of 75 the trunk circuit TC, which is connected to conductors 7 and 9 by way of contacts of backbridge relay 11, operates over the calling line and closes a circuit for release relay 12 at its upper armature, at the same time reversing the connections between the windings of back-bridge relay 11 and the talking conductors. When release relay 12 responds to 80 the closure of its circuit, it places a ground potential on the incoming release trunk conductor 8 by way of the upper winding of the induction coil 14, thereby providing a holding 85 circuit for the switches LS and S.

Signalling the operator

Release relay 12 also places a ground potential on conductor 41, thereby closing a circuit through contacts of relay 17 for the ringing-start relay 15. Relay 15 thereupon 95 operates and locks itself to conductor 41 by way of the middle-upper armature of relay 11, at the same time, applying ringing current to the trunk conductors 23 and 24 at its upper and lower armatures, by way of the corresponding armatures of relay 17. At the 100 same time, the placing of ground potential on conductor 41 results in the closure of a circuit through contacts of relay 17 for the timer relay 16. Relay 16 thereupon operates and closes a circuit for relay 17 by way of 105 contacts of the latter relay. Relay 17 does not respond immediately to the closure of this circuit, because relay 16 is a vibrating-contact relay, having a weight attached to the contact thereof which causes the contact to vibrate for an interval before a continuous 110 connection is made.

Stopping the flow of ringing current

As soon as the contact of relay 16 has ceased 115 to vibrate, relay 17 operates and locks itself to conductor 41; disconnects relay 16 from conductor 41 and prepares a new circuit for it, whereupon relay 16 deenergizes; disconnects the ringing current and closes points in the talking circuit at its upper and lower armatures; and at its inner-lower armature it transfers the vibrating contact of relay 16 from its own winding to the winding of the tone-cut-off relay 13. Relay 13 is rendered 120 slow-acting by the usual copper collar on the armature end thereof so that it does not respond in the time required for relay 16 to fall back after its circuit has been opened at 125 the inner-upper armature of relay 17.

The ringing flow of current has now been discontinued by the operation of relay 17, but relay 15 remains operated in spite of the opening of its initial circuit at contact of relay 17, because of the above-mentioned locking circuit established for this relay through its own inner-upper contacts by way of middle-upper armature of back-bridge relay 11 and conductor 41, grounded at contacts of relay 12.

With relay 15 operated, a characteristic ring-back tone is placed on the lower talking conductor from the ring-back-tone conductor 27, indicating to the calling subscriber that the operator is now being signalled.

In the manual office, the above-described momentary application of ringing current to the trunk line causes an operation of the line relay 18, whose upper winding is normally included in a bridge circuit across the talking conductors of the trunk line. Upon operating, relay 18 closes a locking circuit for its lower winding at its lower contacts, and at its upper contacts it closes a circuit for the lamp 25 L to signal the operator.

The operator answers

The operator responds to the lighting of the lamp L by inserting the plug of an idle 20 cord circuit, the plug P of the cord circuit CC for example, into the jack J. When this occurs, current flows over the sleeve of the plug and jack through sleeve relays 19 and 20 in series. Relay 19 disconnects the upper winding of relay 18 from in bridge of the talking conductors, at the same time opening the locking circuit of relay 18, whereupon relay 18 falls back and the lamp L is extinguished.

40 In the cord circuit CC, relay 20 energizes in series with relay 19, while at the same time the polarized supervisory relay 21 energizes over the talking conductors of the trunk line in series with back-bridge relay 25 11 of the trunk circuit TC. With relays 20 and 21 operated, a circuit is closed through contacts of both relays for the connecting relay 22, which operates to connect the operator's headset conductors 29 and 30 across 30 the talking strands of the cord circuit.

Applying the class-tone current

In the trunk circuit TC, when back-bridge relay 11 energizes over the trunk line in 55 series with the polarized supervisory relay 21 of the cord circuit CC, it reverses the connections between the incoming talking conductors 7 and 9 and the windings of line relay 10 for the purpose of transmitting back a supervisory signal which is of utility in certain cases, as is well known.

Back-bridge relay 11 also closes a multiple holding circuit for release relay 12 at its inner-upper armature; and at its middle-upper armature it opens the locking circuit of

the ring-start relay 15 and closes a new circuit for timer relay 16. The ring-start relay 15 now falls back and terminates the application of ring-back-tone current to the lower talking conductor to indicate to the subscriber that the operator has responded. The new circuit for relay 16 closed by contacts of relay 11 includes the operated inner-upper armature of relay 17. When relay 16 operates at this time it closes a circuit through the operated inner-lower armature of relay 17 for the tone-cut-off relay 13, which relay does not operate for the time being because of the time interval required for the vibrating contact of the timer relay to stop its vibration and make continuous contact.

As a further result of the operation of back-bridge relay 13, the direct ground connection normally applied to the right-hand terminal of the lower winding of relay 11 is replaced by a ground connection through the inner-lower armature of relay 11, normally closed contacts controlled by the armature of the tone-cut-off relay 13, and the lower winding of the induction coil 14. By this connection, the characteristic tone current flowing from the secondary winding of the transformer 25 and through the operating magnet 1 and associated relay 2 to the release trunk conductor of the established connection and thence to ground by way of the upper winding of the induction coil 14 causes a characteristic tone current to flow to the talking circuit by way of the lower winding of the induction coil 14 and the lower winding of the back-bridge relay 11. The tone produced by this flow of current may be heard by the subscriber at 50 station A and also by the operator, whereby the operator learns what class the calling line is in.

Terminating the class-tone current

After the interval for which it is adjusted, the vibrating contact of the timer relay 16 ceases to vibrate, whereupon the tone-cut-off relay 13 responds and re-applies ground potential directly to the right-hand terminal of the lower winding of back-bridge relay 11, at the same time open-circuiting the lower winding of the induction coil 14.

The momentary application of the distinctive tone current has been terminated, and the subscriber and operator may now converse with each other as desired, following which the connection may be further extended by way of the cord circuit CC, in which case the relay 22 is caused to fall back and disconnect the operator's headset conductors from the talking strands of the cord circuit.

Repeating the tone signal

In case the operator wishes to verify the tone signal initially heard, he may cause the

tone signal to be repeated by merely removing the plug P momentarily from the jack J and again inserting the plug. The effect of this operation is to momentarily deenergize 5 the back-bridge relay 11 of the trunk circuit TC to momentarily open the circuit of relays 16 and 18, whereupon both relays fall back and are re-operated in the hereinbefore described manner to terminate the new application of tone current which is made when 10 back-bridge relay 11 re-operates with tone-cut-off relay 13 in a deenergized condition.

Releasing the established connection

15 After the subscriber at substation A has replaced his receiver and caused the operator to receive a disconnect signal at the lamp controlled by the battery feed relay 21, when the connections to the back-bridge relay 11 are reversed, and the operator has removed the plug P from the jack J and allowed the back-bridge relay 11 of the trunk circuit TC to restore, the circuit of release relay 12 is finally opened, whereupon relay 12 falls back 20 and permits relays 13, 16, and 17 to restore, at the same time disconnecting ground potential from conductor 8 to permit the selector S to release and the lineswitch LS to restore to normal condition.

25 16. What is claimed is:

1. In a telephone system, a subscriber's line identified by a distinctive tone, a trunk line, means for extending a call from said subscriber's line to the trunk line, means for 30 answering the call, and means for applying said tone to the trunk line and for removing the same responsive to the answering of the call.

2. In a telephone system, a subscriber's line, a source of tone associated with said line, a trunk line, means for extending a call from said subscriber's line to said trunk line, means for answering the call, means operative for connecting said tone source to the trunk line and for subsequently disabling the tone source, and means responsive to the answering of the call for operating said last means.

3. In a telephone system, two exchanges, an interconnecting trunk line, means in one exchange for extending a call to the other exchange via said trunk line, means in the other exchange for answering the call, a source of tone in said one exchange, and means responsive to the answering of the call for momentarily applying tone from said source to the trunk line and for then terminating the application.

4. In a telephone system, two exchanges, an interconnecting trunk line, means in one exchange for extending a call to the other exchange via said trunk line, a link circuit in said other exchange for answering and further extending the call, a source of tone

in said one exchange, and means responsive solely to the connection of said link to the trunk line to answer the call for connecting said tone source to the trunk line and for disconnecting it at the end of a predetermined interval.

5. In a telephone system, a trunk line connecting an automatic exchange and a manual switchboard, subscribers' lines of different classes in the automatic exchange, the lines 70 of each class being identified by a separate tone supplied by tone sources associated with the lines, means for extending a connection from a calling line to the switchboard via said trunk line, a link circuit at the switchboard adapted to connect with the trunk line for answering the call, and means whereby the tone identifying the calling line is automatically applied to the trunk line and subsequently removed therefrom responsive to the connection of said link circuit with the trunk line.

6. In a telephone system, a trunk line including two talking conductors and a test conductor, a link circuit adapted to be connected to the trunk line, and means automatically responsive to the connection of said link to the trunk line for inductively connecting said test conductor and one of said talking conductors and for then disconnecting them at the 85 end of a short interval.

7. In a telephone system, a trunk line extending from a first switchboard to a second switchboard, said second switchboard being a manual switchboard, means at the first switchboard for extending a connection to said trunk line and for signalling the operator at the second switchboard over said trunk line, means under the control of the operator at the second switchboard whereby the operator can respond to the said signal by placing herself in telephonic communication with the trunk line, means also responsive to the last named means for setting up a supervisory condition over said trunk line, means at the first switchboard for making a momentary characteristic application of tone current to said trunk line, and means responsive to said supervisory condition being set up for initiating the operation of the last-named means.

8. In a telephone system, a line identified by a distinctive tone, a trunk line extending to a manual switchboard, means for extending a call from said line to said trunk line, means including a plug and a jack at said switchboard for answering said call, and means responsive to the insertion of the plug into the jack pursuant to the answering of the call for initiating and terminating a momentary application of said distinctive tone to said trunk line.

JOHN A. BURGENER.
